FUSE MOUNTING

Alfred Corbett, Irwin, Pa., assignor to National
Electric Products Corporation, a corporation
of Delaware

Application April 7, 1937, Serial No. 135,501

4 Claims. (Cl. 200—133)

This invention relates to an electrical fuse mounting.

More particularly my invention relates to the combination of a plug fuse socket arranged for the exposure of a central feed contact at the base thereof with a deck arranged for connection therebeneath with a current source.

In a more general sense my invention relates to a plug fuse socket having integral therewith means arranged for connection to a line circuit, and by means of which the socket may be positively connected with an underlying insulating structure of any form independently of the central contact element of the fuse socket.

As shown, the fuse socket of my invention comprises a selective contact screen through which an appropriately dimensioned central contact may be projected to make electrical contact with an underlying live contact element.

In the accompanying drawings Fig. I is a front elevation of a fuse box partially broken away to show in front elevation the fuse mounting in position therein.

Fig. II is a cross-sectional view, taken on the plane of section line II—II of Fig. I, showing the fuse mounting of my invention in position therein.

Fig. III is an exploded view, taken partly in elevation and partly in vertical section, showing the fuse-carrying deck, the plug fuse socket, and a cover plate in position for installation of the fuse socket on the deck.

Fig. IV is a vertical sectional detail view of the plug fuse socket of my invention, showing the circuit contact integrated therewith, and binding screws in position for mounting the socket to the fuse-carrying deck.

Fig. V is a bottom plan view of the fuse socket and the circuit contact member integrated therewith.

Fig. VI is a fragmentary, vertical, sectional view of the fuse-carrying deck, showing the fuse socket partially in elevation and partially in vertical section mounted thereon.

In the drawings reference numeral 1 designates a fuse box in which are installed a plurality of fuse-carrying decks. These decks 4, as shown in Fig. II of the drawings, are mounted in assembly with buss bars 3; and, as is shown in Figs. I and II, carry cover plates 2 which are spaced bodily from the face of the decks to surround the upper edges of upwardly open sockets 5 for the reception of plug fuses.

Figs. II, III, and VI of the drawings show the mounting of a circuit contact to a fuse socket,

and in the cooperative mounting of the fuse socket and its exterior contact and contact attachments on the fuse-carrying deck 4. The features comprised in my improvement may be applied to any fuse socket of usual construction for the reception of a fuse of the screw plug type comprising a downwardly projected center contact and arranged to complete a circuit through said center contact to an outwardly disposed contact, which latter is in usual practice the circuit contact. The improvements, however, have particular utility in cooperation with a special arrangement providing for selectivity in the fuses which may be used with a particular socket, and which arrangement precludes the use of a center contact screw, or rivet, for attaching the fuse socket to an underlying insulating body.

In its fundamental features this illustrated fuse socket comprises an exterior metallic shell 6, an interior insulating cylinder 7, and a bottom structure comprising a plate 8 of insulating material perforate centrally at 8a, and an interior threaded shell 9. Desirably, the base of the socket comprises a metallic plate 10 have a central opening 10a in line with the opening 8a through the insulating plate but of a lesser diameter, and a centrally perforate light-weight insulating disc 24 overlying the metallic disc. With this arrangement central feed contact depends upon the projection of a central contact carried by the fuse through the central opening in the base of the socket. This may be effected only by a fuse, such as the fuse 11 shown, which has a center contact 12 of such restricted diameter that it may project through the opening 10a, which is the most restricted of the central openings, to make electrical contact with a live contact, such as the contact screw 17 shown in the drawings.

With this structure, the mounting means primarily comprise a contact element 14 of conductive metal, which is projected radially from the fuse socket adjacent the base of the socket. This contact element is secured to the cylindrical body of the fuse socket for permanent integration therewith, and in electrical contact with the exterior metallic shell of the socket. This permanent integration may be by welding or soldering the contact to the shell, but I may alternatively utilize the mode of permanent attachment which is shown in the drawings.

As shown, the region of the contact element 14 which lies beneath the fuse socket is formed as a torus 15 which lies against the non-conductive base plate 8 in a position in which it does not obstruct the central opening 8a in the base plate.

As shown, throughout a portion of its circumference the torus 15 of the contact member 14 is clamped to the insulating base plate 8 by a flange or lip 16, which is inturned at the lower edge of the exterior metallic shell 6, and is forced firmly against the under surface of torus 15, firmly and permanently to engage the radial contact element 14 to the body of the fuse socket.

This arrangement is useful for the attachment 10 of any fuse socket for receiving a fuse of the screw plug type to an underlying insulating body. It is of particular utility in attaching a fuse socket of the specialized tamper-proof and selective type herein shown to an underlying insulating body, and is of particular utility in 15 mounting a socket of that type on a fuse-carrying deck, such as the fuse-carrying deck shown, which has a live or feed contact extended therethrough to provide for the making of feed contact to the fuse at the upper surface of the deck.

In this specific assembly the deck 4 has extended therethrough a screw 17, which is adapted to carry an element for making electrical contact with a buss bar 3 beneath the deck, or is arranged of itself to make electrical contact with such buss bar. The head 17a of the contact screw lies upon, and projects slightly above, the upper surface of the deck 4. In establishing an electrical circuit through the fuse, the center 25 contact 12 of the fuse is caused to project through the central opening 8a in insulating base plate 8 a distance sufficient to bring the center contact of the fuse firmly to bear against the head 17a of the contact screw 17.

35 In mounted position of the fuse socket on the fuse-carrying deck, as shown in Fig. VI, the radially extended contact 14, which as usual is here the circuit contact of the fuse, raises the body of the fuse socket sufficiently from the 40 upper surface of the deck 4 that the head 17a of contact screw 17 is received in the space defined by the torus 15 which forms the inward portion of the contact member. In the radially extended body of contact member 14 there is a 45 pair of openings 18 and 19, for securing the contact member and fuse socket assembly to the deck, and for making circuit connection to the contact member. A screw 20, passed through opening 18 and having threaded engagement in 50 a thimble 21 inset in the body of the deck, serves to secure the contact member and the socket assembly to the deck. Dependent around opening 19 is a fillet 19a, which enters a cavity 22 in the deck. A binding screw 23 has a threaded engagement in the thickness of the contact body 55 surrounding opening 19 and in the fillet 19a, and projects into the cavity 22 in the deck.

It will be seen that the fuse socket assembly is secured to the fuse-carrying deck by means of 60 the radially extended circuit contact, and is not secured by means of the centrally disposed feed contact. Also, the socket assembly receives within its general structure, but outside the tamper-proof interiorly disposed elements of the 65 socket, the central feed contact which is extended through the deck structure.

It will readily be seen that the fuse socket mounting is adapted operatively to secure a fuse socket to underlying insulating structures other than the deck shown; and that for such general purpose it is particularly accommodated to the 5 use of cooperative tamper-proof and selective features in the fuse and fuse socket. It is, however, of general utility, since the use of the radially extended circuit contact integral with the fuse sockets, for mounting the fuse socket 10 on an underlying insulating structure, makes for convenience in making mounted assembly of the fuse socket in a panel board, or like structure, which comprises a great number of fuse sockets.

I claim as my invention:

1. As an integral element, a socket for plug fuses comprising a cylindrical shell of electrically conductive metal, a non-conductive base mounted in said shell, a peripherally extended contact bar having a portion lying beneath said 20 non-conductive base and within the periphery of the shell, and a flange projected radially inward from the lower edge of the shell and engaging the contact bar between it and the non-conductive base in permanent integration in the socket 25 structure and in electrical contact with the shell.

2. A fuse mounting assembly comprising the combination of a fuse-carrying insulating deck having extended therethrough a contact member adapted to make electrical contact with a live 30 electrical conductor beneath the deck and to make electrical feed contact with a fuse above the deck; with a fuse socket comprising a metallic outer shell, a base providing in said metallic shell and arranged to permit selective projection of a 35 fuse contact therethrough to meet the deck-carried contact, and a peripherally extended contact member integrated in the fuse socket structure and in permanent electrical contact with the outer metallic shell of the fuse socket.

3. As an integral element, a socket for plug fuses comprising a cylindrical shell of electrically conductive metal, a non-conductive base mounted in said shell, a peripherally extended contact bar having a portion lying beneath said 45 non-conductive base and within the periphery of the shell, in permanent integration with the shell, and an opening for the center contact of a plug fuse in said non-conductive base and removed both from said conductive shell and the peripherally extended contact bar permanently integrated therewith.

4. As an integral element, a socket for plug fuses comprising a shell of electrically conductive 50 metal, a contact bar having a portion lying within the periphery of the shell at the lower end thereof in permanent integration with the shell and a portion extended peripherally beyond the shell, and an opening in the portion of the contact bar lying within the periphery of the shell 55 for projection of the center contact of a plug fuse downwardly from the shell and out of contact with the said contact bar.

ALFRED CORBETT. 6
